UNITED STATES PATENT OFFICE

JOHN GRANT, OF LOS ANGELES, CALIFORNIA

PROTECTED UNDERREAMER

Application filed March 10, 1928. Serial No. 260,713.

This invention has relation to expansive reamers or underreamers of the kind used for well drilling, and it relates most particularly to means and arrangements for protecting such a reamer against entry of muddy fluid, sand and silt. All expansive reamers and underreamers are more or less liable to become filled and clogged with deposits of solid matter; and in some cases they may become so clogged that they will not properly expand upon passing out of the bottom of the casing. It is a general object of this invention to provide a protective means to prevent the reamer from becoming clogged while it is being lowered to its place of operation, and so that it will infallibly expand when it passes below the casing. When once expanded and put into operation, there is another protective means, and the water or fluid circulation is arranged and directed, to keep the reamer clean so that it will not be clogged against contraction when removal is desired.

I describe my invention as applied to a particular and specific type of reamer; but it will be readily understood that the invention is not necessarily restricted to the particular reamer here set forth, but is capable of application to other kinds and types of reamers having other particulars of design. In a reamer in which the body is slotted and the cutters or cutter-carriers move longitudinally in the slots for contraction and expansion, the end parts of the slots are necessarily left open—the cutters or cutter-carriers are necessarily shorter than the slots. It is through the open parts of these slots that the muddy fluid finds its major entry to the interior parts of the reamer; and my invention is designed to close the open parts of such slots when the reamer is in its expanded position, as well as to close the open parts of the slots when the reamer is contracted. How this is done in the particular design here shown will be best understood from the following description, and from a consideration of that description the invention itself will best be apparent. For the purposes of detailed description of the present preferred embodiment I refer to the accompanying drawings in which

Figure 1 is a central longitudinal sectional view of a reamer equipped in accordance with my invention, this view showing the parts in contracted position.

Figure 2 is a similar view showing the parts expanded.

Figure 3 is a fragmentary view showing a modification of the invention.

Figure 4 is an enlarged cross section on line 4—4 of Figure 1.

The typical reamer illustrated in the drawings has a substantially tubular body 10 provided with a plurality of longitudinal slots 11, which I here show as 3 in number, although the number of slots and therefore the number of cutters is largely a matter of choice. Inside this body there is a central mandrel 12 joined at its upper end to the body at the screw-threaded joint 13 and depending centrally in the bore 14 of the body, as illustrated. The whole mandrel may be either made in one piece or its lower part may be in the form of a removable extension tube 15 which extends to a point near the lower end of the body, the lower end of tube 15 being close to the tool joint pin 16 of drilling bit 17, which is attached to the lower end of the body. The cutter-actuating spring 18 surrounds the mandrel tube 15 and rests at its lower end upon a spring seat collar 19, which collar rests upon tool joint pin 16 and surrounds the lower end of tube 15 to steady the lower end of the mandrel against vibration and thus to insure the mandrel against breakage. This compression spring 18 acts at its upper end on a cutter propeller 20, which is here shown as cylindric in form and slidably, but snugly, fitting the body bore 14. In its lowermost position this propeller 20 is substantially below the lower ends of slots 11 and in its upper position, as shown in Figure 2, its lower end is still somewhat below the lower ends of slots 11; so that in all its positions this cylindric or piston like propeller 20 closes the lower part of bore 14, and the smaller spring chamber bore 14^a, against entry of fluid through the slots 11. There is thus no entry opening for muddy fluid into the spring chamber below propeller 20, except through the very

slight clearance spaces around propeller 20 and between the propeller and the mandrel tube 15. And the propeller fits around the mandrel tube 15 as closely as is consistent with its sliding action on the tube, so that only a very slight clearance space is left at that point.

To provide for the washing out of any fine silt which may find its way into the spring chamber during operation, I provide that a part of the circulating water shall pass into and through the spring chamber during operation. It will be readily understood that when the reamer is in its contracted position, as shown in Figure 1, and is being lowered through the pipe to its place of operation, any small accumulation of fine silt or mud which may find its way into the spring chamber will not, to any great extent, prevent expansion of the spring or upward movement of propeller 20. The mud or silt accumulation that might effectively prevent upward movement of the propellers and cutters is that accumulation which may take place above the cutters; and prevention of that is provided for in the manner which I hereinafter explain. As far as the spring chamber is concerned, it is primarily necessary to prevent mud or silt accumulation in it when the parts are in the expanded position of Figure 2; and this is done first by the fact that propeller 20 closes the lower ends of slots 11, and second, by the fact that the water circulation through the expanded spring chamber constantly washes out any such accumulation as might otherwise take place through the small clearance spaces. The water circulation comes down through a longitudinal circulation passage 25 in the mandrel and is extended on through the tube 15. This circulation passes out of the tube at its lower end and thus goes to the circulation passage 26 of drill bit 17 and may also, due to a somewhat loose fit of collar 19, pass from the lower end of tube 15 up into the bore 14^a. But the tube may also have perforations, such as shown at 27, to put circulating water directly into the bore from the tube. And discharge passages 28 are provided extending upwardly and outwardly, at the lower ends of the slots and under the cutters, so as to discharge a certain amount of circulation upwardly under the cutters. By this circulation through the spring chamber, it and the spring are kept washed free of any small accumulation of solid matter during the operation of the tool.

The cutting elements of the tool are here shown as comprising roller cutters 30 mounted in carriers 31. The mandrel 12 has an upper and comparatively large cylindric part 12^a terminating at its lower end in a downwardly facing diagonal shoulder 12^b. In the collapsed position of the cutters, shown in Figures 1 and 3, the upper ends of the car-

riers 31 rest inwardly against a reduced portion 12^c of the mandrel directly below shoulder 12^b. When the tool emerges below the casting and the cutters are allowed to expand, the action of spring 18 and propeller 20 is to move the cutter carriers and cutters upwardly, the diagonal surface of 12^b causing the upper ends of the carriers to move outwardly, and then the cutter carriers move directly upwardly to the position of Figure 2. In that position the upper ends of the carriers bear inwardly against the part 12^a of the mandrel and the lower ends of the carriers bear inwardly against the lower tapered part 12^d of the mandrel. The carriers are provided at their side edges with wings 31^a, indicated in dotted lines in Figure 4, which overhang the edges of slots 11 to prevent the carriers from moving outwardly further than the expanded position of Figure 2.

The upper large cylindric part 12^a of the mandrel does not entirely fill the bore 14, but leaves an annular space between itself and the wall of the bore. In this annular space, as shown in Figures 1, 2 and 4, I provide a sealing sleeve 35 which surrounds, and is longitudinally slidable on, the cylindric portion 12^a of the mandrel and fits snugly but slidably in bore 14. The length of this sleeve is such that, resting at its lower end upon the upper ends of the carriers 31, it entirely closes the otherwise open upper ends of slots 11 when the parts are in the position of Figure 1. When the cutters slide upwardly the sleeve is moved upwardly above them into the position shown in Figure 2. When the cutters are again pushed downwardly the sleeve 35 drops down with them and again assumes the position of Figure 1. Thus the sleeve 35 at all times closes the upper ends of slots 11 when the upper ends of those slots are not closed by the cutter carriers themselves.

In order to insure that the sleeve 35 shall not be accidentally moved upwardly when the cutters are held in their lower positions of Figure 1, I may provide a small latch which may conveniently be mounted in a slot 36 in the mandrel, the latch being pivoted at 37 and having a latch head 38 at its upper end adapted to swing over the upper edge of sleeve 35. The lower end 39 of the latch is in such a position as to be engaged by the upper end of carrier 31 when that upper end is in the position of Figure 1. In this position the upper end of the carrier has been moved inwardly under the mandrel shoulder 12^b, and this inward movement of the upper end of the carrier, causing inward movement of the lower end 39 of the latch, causes the upper end of the latch to swing outwardly and over the upper edge of sleeve 35. A small flat spring, shown at 40 in Figure 2, urges the latch head 38 back away from sleeve 35, so that when the upper end of car-

rier 31 moves upwardly and outwardly from the position of Figure 1, the lower end 39 of the latch may move outwardly and the upper latch head 38 move inwardly to release the sleeve 35 and to allow it then to move up with the cutters.

The protective sleeve 35 has been described as being located on the inside of body 10 and that is the location which I prefer. In that location the protective sleeve is not liable to be disturbed or injured by forcible contact with any exterior object. But in a broad sense the sleeve may be otherwise located and still perform its proper function.

15 For instance, in Figure 3 I have shown an exterior sleeve 35^a which is slidable around the outside of body 10, its lower end resting upon the upper ends of carriers 31; the sleeve moving up with the carriers as before described, and covering the open upper ends of slots 11 when the carriers are in their lower and collapsed positions. Such a sleeve, mounted on the outside of the body may be made of any suitable material. Situated in

25 that position it may be subject to some considerable wear. And it may thus be made of a material calculated to resist such wear. On the other hand it may be made of a relatively soft material which will wear out or break up when the cutters move to their upper positions or when subjected to frictional contact with the side of the hole while the reamer is in operation. Thus in the form of

35 Figure 3 the sleeve may be made of a thin and soft sheet metal which, instead of sliding vertically on the body, will be torn or crumpled upwardly by the cutters when they are forced upwardly by the heavy spring 18. Or the sleeve may be even made of such a material as rubber—a rubber sleeve somewhat distended and placed in the position shown in Figure 3. Any such sleeve is protected from contact with the casing by the fact that the upper ends of the carriers project further outwardly than any other parts of the reamer and therefore take the frictional contact with the casing as the tool is being lowered. Thus in the particular form of reamer here shown the upper ends of carriers 31 are shown provided with renewable wear washers or members 50 which project out at least as far as the cutters 30 and thus exclusively make contact with the casing.

I claim:

55 1. In a reamer of the character described, the combination of a longitudinally slotted tubular body, cutters movable longitudinally in the body slots and filling portions of the slot lengths from side to side, and a slot closing sleeve resting upon the upper ends of the cutters and adapted to close the otherwise open upper ends of the slots when the cutters are in position at the lower ends of the slots.

60 2. In a reamer of the character described, the combination of a longitudinally slotted

tubular body, cutters movable longitudinally in the body slots and filling portions of the slot lengths from side to side, and slot closing members movable with the cutters one in contact with one end of the cutters and the other in contact with the other end of the cutters.

65 3. In a reamer of the character described, the combination of a longitudinally slotted tubular body, cutters movable longitudinally in the body slots and filling portions of the slot lengths from side to side, and slot closing members fitting the internal bore of the body and slidably therein and contacting one with one end of the cutters and the other with the other end of the cutters.

70 4. In a reamer of the character described, the combination of a longitudinally slotted tubular body, cutters movable longitudinally in the body slots and filling portions of the slot lengths from side to side, a cutter propeller fitting and slidable in the internal bore of the body and engaging the lower ends of the cutters, a spring urging said propeller upwardly, and a slot closing sleeve resting upon the upper ends of the cutters and engaging the body closely at the upper ends of the slots.

75 5. In a reamer of the character described, the combination of a longitudinally slotted tubular body, cutters movable longitudinally in the body slots and filling portions of the slot lengths from side to side, a cutter propeller fitting and slidable in the internal bore of the body and engaging the lower ends of the cutters, a spring urging said propeller upwardly, and a slot closing sleeve resting upon the upper ends of the cutters and fitting slidably in the body bore.

80 6. In a reamer of the character described, the combination of a longitudinally slotted tubular body, cutters movable longitudinally in the body slots and filling portions of the slot lengths from side to side, a cutter propeller fitting and slidable in the internal bore of the body and engaging the lower ends of the cutters, a spring urging said propeller upwardly, and a slot closing sleeve resting upon the upper ends of the cutters and engaging the body closely around the upper ends of the slots, said spring being housed within the lower part of the body bore below the propeller, and means for passing circulating fluid through that part of the body bore below the propeller.

85 7. In a reamer of the character described, the combination of a longitudinally slotted tubular body, cutters movable longitudinally in the body slots, and a slot closing sleeve resting upon the upper ends of the cutters and adapted to close the otherwise open upper ends of the slots when the cutters are in position at the lower ends of the slots, and a cutter actuated latch adapted to hold the slot closing sleeve in its lowermost position.

90 8. In a reamer of the character described,

a substantially tubular body having longitudinal slots in its wall, cutters mounted in the said slots and movable longitudinally therein, a central mandrel extending vertically through the longitudinal bore of the body, said mandrel and cutter being formed so that upward movement of the cutters in the slots causes their outward expansive movement, a cutter propeller vertically movable in the lower part of the body bore below the cutters, said propeller slidably fitting the body bore so as to close the lower ends of the body slots when moved upwardly, a spring in the body bore below the propeller and urging it upwardly, a slot closing sleeve surrounding the upper part of the mandrel and slidably fitting in the upper part of the body bore above the cutters and closing the upper ends of the body slots when the cutters are in their lower positions, said sleeve being movable upwardly with the cutters as they move upwardly in the slots.

9. In a reamer of the character described, a substantially tubular body having longitudinal slots in its wall, cutters mounted in the said slots and movable longitudinally therein, a central mandrel extending vertically through the longitudinal bore of the body, said mandrel and cutter being formed so that upward movement of the cutters in the slots causes their outward expansive movement, a cutter propeller vertically movable in the lower part of the body bore below the cutters, said propeller slidably fitting the body bore so as to close the lower ends of the body slots when moved upwardly, a spring in the body bore below the propeller and urging it upwardly, a slot closing sleeve surrounding the upper part of the mandrel and slidably fitting in the upper part of the body bore above the cutters and closing the upper ends of the body slots when the cutters are in their lower positions, said sleeve being movable upwardly with the cutters as they move upwardly in the slots, the mandrel extending downwardly through the body to a point near its lower end and below the cutter propeller, the mandrel having a fluid circulation passage with an outlet into the body bore below the propeller, and a body having discharge passages leading from the bore below the propeller for effectuating circulation through the bore below the propeller and around the propeller actuating spring.

53 In witness that I claim the foregoing I have hereunto subscribed my name this 4th day of February, 1928.

JOHN GRANT.
